PUMP CONTROL SYSTEM

Rowland B. Drescher and Alfred C. Wenzel, Chicago, Ill., assignors to Republic Flow Meters Company, Chicago, Ill., a corporation of Illinois

Application September 25, 1944, Serial No. 555,740

14 Claims. (Cl. 103—11)

1

This invention relates to a pump control system and more particularly to a system for controlling the operation of pumps, compressors and the like to prevent back surges or so-called "pumping."

In the operation of pumps and compressors and particularly of centrifugal pumps and axial flow compressors, if the flow is throttled to an amount sufficient to raise the pressure above a critical value for any given pump speed back surges from the discharge line into the pump occur resulting in a so-called pumping condition and setting up vibrations and excessive strains on the machinery. To eliminate this condition it has been proposed to provide blow off valves connected to the pump discharge and adapted to be opened when the flow thru the pump falls below a predetermined minimum.

It is one of the objects of the present invention to provide a pump control system in which the blow-off valve is controlled in accordance with the relationship between discharge pressure and flow to prevent the establishment of a pumping condition.

It is another object of the invention to provide a pump control system in which both the blow off valve and the pump speed are controlled in accordance with functions of the discharge pressure and the flow thru the pump.

Still another object is to provide a pump control system in which the effect of the discharge pressure on the blow off valve is automatically varied to produce any desired control operation. In one preferred embodiment the discharge pressure operates thru a cam mechanism which may be shaped to produce the desired control of the blow off valve.

A still further object is to provide a pump control system in which the pump speed is controlled by the balance between an adjustable loading pressure and the pump discharge pressure and the blow off valve is controlled in accordance with the balance between the loading pressure and a function of the flow thru the pump.

The above and other objects and advantages of the invention will be more readily apparent from the following description when read in connection with the accompanying drawing, in which—

Figures 1 and 2 are diagrammatic views of alternative pump control systems embodying the invention.

In the system shown in Figure 1 an axial flow type pump or compressor 10 is driven by any desired type of power means such as a turbine 11

2

and discharges into a main discharge conduit 12 which may lead to any desired point of use. The speed of the turbine may be regulated in any desired manner, as for example, by a governor 13, and a blow-off valve 14 is connected to the conduit 12 and discharges to atmosphere at any desired point. The blow-off valve is operated by a regulator indicated generally at 15 which will open the valve 14 to varying degrees in accordance with pressure supplied thereto thru a pipe 16. The regulator 15 may be of any desired construction such, for example, as that shown in the patent to Rosenberger No. 2 220,176.

In accordance with the present invention, the blow-off valve is controlled in response to variations in the discharge pressure and in the flow thru the pump. For this purpose a pitot tube 17 is arranged in the discharge conduit 12 anterior to the connection to the blow off valve 14. Tube pipes 18 and 19 are connected to the pitot tube, the pipe 18 carrying the upstream pressure and the pipe 19 carrying the downstream pressure. The pipes 18 and 19 are connected thru condensate collectors 21 to the opposite sides of a flexible diaphragm 22 which is connected to one end of a balance beam 23 pivoted at 24 and forming a part of a regulator. The diaphragm 22, therefore, exerts on the beam 23 a force proportional to the differential pressure across the pitot tube tending to tilt the beam clockwise.

The force of the diaphragm 22 is balanced by a diaphragm 25 supplied on its upper side with loading pressure thru a loading line 26 for tending to tilt the beam counter-clockwise. The beam is connected thru a link 27 to an adjustable bleed valve 28 to control the bleed valve in accordance with the balance between a function of the flow thru the pump and the loading pressure. While the regulator has been shown diagrammatically with the beam 23 connected directly to the valve 28, it will be understood that any desired type of regulator including power relay mechanism, could be used to operate the valve.

Fluid is supplied to the valve 28 from any desired source thru a line 31 having a restriction 32 therein so that the extent of opening of the valve 28 determines the pressure in the line 31 beyond the restriction. Thus, the valve 28 produces a regulated loading pressure in the line 31 which may be connected directly to the governor 13 and to the regulator 15 thru the pipe 16 as shown. The loading pressure supplied to the diaphragm 25 thru the pipe 26 is produced in accordance with the discharge pressure in the pipe

12. For this purpose the pipe 18 is connected to a chamber 33 closed on one side by a flexible bellows 34. The pressure in the chamber will move the bellows against its natural resilience but if desired, an additional spring could be provided to urge the bellows to expand against the pressure in the chamber. The bellows is connected to one end of a lever 35 fixedly pivoted at 36 and carrying at its opposite end a cam follower engageable with an elongated cam 37. The cam 37 is pivoted at 38 on a bar 39 which is supported by a link 41 and by a hollow discharge tube 42. The tube 42 is connected to and opens thru the end of a bellows 43 closing one end of a pressure chamber 44. An extension on the cam is movable toward and away from the outer end of the tube 42 variably to restrict the discharge therethrough, thereby to control the pressure in the chamber 44. A spring 45 is preferably provided urging the lower end of the lever 37 toward the tube 42.

The chamber 44 is supplied with fluid such as air under pressure thru a pipe 46 under the control of a pressure regulator 47. An orifice 48 is provided in the supply line so that variable restriction of the discharge end of the tube 42 will regulate the pressure in the chamber 44. The pipe 26 is connected to the chamber 44 to conduct regulated pressure therefrom to the diaphragm 25.

In operation the regulator 23 will control the valve 28 to produce a regulated loading pressure in the line 16 which acts on the regulator 15 to control opening of the blow-off valve. If the rate of flow thru the compressor is high enough relative to the pressure existing in the discharge conduit so that no pumping will occur, the blow-off valve will be closed. At this time, the turbine will operate at a speed determined by the setting of the governor or other control to maintain the desired pressure and rate of flow in the discharge conduit 12. If the demand should decrease to a point where pressure in the discharge conduit increases relative to the rate of flow to a sufficient degree to cause pumping, the control system will operate to open the blow-off valve. When this condition occurs the pressure increase is transmitted thru the line 18 to the chamber 33 to rock the lever 35 counter-clockwise moving the follower away from the cam 37. The spring 45 may then move the lower end of the cam lever toward the discharge tube 42 to increase the pressure in the chamber 44. This will move the bellows 43 to the left moving the discharge rod and the bar 39 to the left until the cam 37 again engages the follower and the system arrives at a balanced condition with an increased pressure in the chamber 44. This increased pressure is transmitted thru the pipe 26 to the diaphragm 25 to rock the beam 23 counter-clockwise and reset the valve 28. It will be understood that the valve 28 may be either opened or closed as desired, in accordance with the setting of the governor and of the regulator 15. Assuming for example, that the valve 28 is opened when the lever 23 rocks counter-clockwise, the pressure in line 16 will be decreased to decrease the loading on the regulator 15 to cause opening of the blow-off valve 14. When the rate of flow thru the pump again reaches a value relative to the pressure such that pumping will not occur, the valve 14 will be closed. This action is produced by the differential pressure acting on the diaphragm 22 in response to flow thru the dis-

charge conduit balancing the loading pressure on the diaphragm 25.

By shaping the cam 37 any desired control can be obtained so that the system will operate at all times with a predetermined relationship between discharge pressure and total flow thru the pump. Thus the system can easily be accommodated to various type of pumps and to various operating conditions.

10 The connection of line 16 to the governor 13 provides a safety control to prevent racing of the turbine. If the turbine speed should increase above a predetermined maximum value the governor 13 will vent the line 16 to reduce the pressure therein. This will cause the regulator 15 to open the valve 14 to increase the flow thru the compressor, thereby increasing the load on the turbine to limit its speed.

15 In the system shown in Figure 2, a pump 50 is driven by a turbine 51 which is controlled by a governor 52. The pump is supplied with air thru an inlet conduit 53 and discharges air under pressure thru a discharge conduit 54 which is provided with a blow-off valve 55.

20 In this system the desired discharge pressure is adapted to be set manually thru a manually controlled pressure regulator 56 which supplies loading pressure to a pipe 57. For controlling the turbine speed the pipe 57 is connected to a diaphragm 58 acting on one end of a weigh beam 59. The weigh beam is balanced by a diaphragm 61 connected thru a pipe 62 to the discharge conduit 54. Balance of the weigh beam is therefore determined by the balance between the loading pressure and the pump discharge pressure.

25 The weigh beam 59 controls a valve member 63 which moves toward and away from a nozzle 64 supplied with fluid such as air thru a restriction 65. Pressure in the nozzle 64 is supplied to the governor thru a pipe 66 to load the governor thereby to control the speed of the turbine.

30 The loading pressure in pipe 57 is also utilized to control opening of the blow off valve 55 and for this purpose the pipe 57 is connected to a diaphragm 67 acting on one end of a weigh beam 68 forming part of a regulator having a power unit 69. The weigh beam is balanced by a diaphragm 71 connected on its opposite sides thru pipes 72 to the inlet pipe 53 on the opposite sides 35 of a restriction 73 therein. As the weigh beam moves in response to unbalance of the diaphragms it causes the power unit to move an arm 74 vertically. The arm 74 is connected thru a link 75 to a blow-off valve 55 to open it.

35 In operation of this system the turbine and pump speeds are regulated thru the governor in accordance with the balance between the loading pressure and the pump discharge pressure. In the event the discharge pressure is below the 40 loading pressure, the valve member 63 will move toward the nozzle 64 to increase the loading pressure supplied to the governor thru the line 66. The governor will, therefore, be additionally loaded to cause the turbine speed to increase 45 tending to bring the pump discharge pressure up to the desired value.

40 In the event the volume of flow thru the pump falls below the critical value at which pumping will occur, the differential across the diaphragm 71 will drop causing the beam 68 to turn clockwise. This will operate the power unit 69 to move the arm 74 in a direction to open the valve 55 to establish the desired minimum flow thru the pump. Since the differential across the diaphragm 71 is a square function of the flow thru

the orifice 13 the relationship between the loading pressure and the flow will be a square relationship. This is desirable since the pump operating curves do not increase linearly with the pump speed so that in all ranges of the operation the regulator will function to maintain a safe minimum flow thru the pump.

While two embodiments of the invention have been shown and described in detail herein, it will be understood that these are illustrative only and are not intended as definition of the scope of the invention, reference being had for this purpose to the appended claims.

What is claimed is:

1. A control system for a pump having a discharge conduit with a blow-off valve therein comprising a regulator for controlling the blow-off valve, control means for controlling the regulator, means responsive to the rate of flow thru the discharge conduit to operate the control means, and means responsive to the pressure in the discharge conduit to modify operation of the control means by the flow responsive means.
  2. A control system for a pump having a discharge conduit with a blow-off valve therein comprising a regulator responsive to the balance between the pressure in the discharge conduit and of the rate of flow thru the pump, and means operated by the regulator to control the blow-off valve.
  3. A control system for a pump having a discharge conduit with a blow-off valve therein comprising a governor for controlling the speed of the pump, a regulator for controlling the blow-off valve, means responsive to the pressure in the discharge conduit variably to load the governor thereby to control the speed of the pump, and means responsive to the rate of flow through the pump to control the regulator.
  4. A control system for a pump having a discharge conduit with a blow off valve therein comprising a governor for controlling the speed of the pump, a regulator for controlling the blow off valve, a regulator responsive to the pressure in the discharge conduit to create a loading pressure, the governor being connected to the last named regulator to control the speed of the pump in response to the loading pressure, and means for operating the first named regulator in response to the rate of flow thru the pump.
  5. A control system for a pump having a discharge conduit with a blow off valve therein comprising a regulator responsive to the balance between the pressure in the discharge conduit and the rate of flow thru the pump, means operated by the regulator to control the blow-off valve, and means operated by the regulator to control the speed of the pump.
  6. A control system for a pump having a discharge conduit with a blow off valve therein comprising a regulator including balance means, means responsive to the rate of flow thru the pump to urge the balance means in one direction, a diaphragm acting on the balance means to urge it in the opposite direction, means responsive to the pressure in the discharge conduit to supply a variable loading pressure to the diaphragm, and means controlled by the regulator to operate the blow-off valve.
  7. A control system for a pump having a discharge conduit with a blow off valve therein comprising a regulator including balance means, means responsive to the rate of flow thru the pump to urge the balance means in one direction, a diaphragm acting on the balance means
  10. 15. 20. 25. 30. 35. 40. 45. 50. 55. 60. 65. 70. 75.
- to urge it in the opposite direction, means to supply a loading pressure to the diaphragm, means controlled in response to the pressure in the discharge conduit to vary the loading pressure, and means controlled by the regulator to operate the blow-off valve.
8. A control system for a pump having a discharge conduit with a blow off valve therein comprising a regulator including balance means, means responsive to the rate of flow thru the pump to urge the balance means in one direction, a diaphragm acting on the balance means to urge it in the opposite direction, a loading line connected to the diaphragm to supply loading pressure thereto, control means to vary the loading pressure, a pressure responsive member movable in response to the pressure in the discharge conduit, means including a cam connecting the pressure responsive member to the control means, and means controlled by the regulator to operate the blow-off valve.
9. A control system for a pump having a discharge conduit with a blow-off valve therein comprising a regulator including balance means, means responsive to the rate of flow thru the pump to urge the balance means in one direction, a diaphragm acting on the balance means to urge it in the opposite direction, a loading line connected to the diaphragm to supply loading pressure thereto, control means to vary the loading pressure, a pressure responsive member movable in response to pressure in the discharge conduit, means including a cam connecting the pressure responsive member to the control means, and means controlled by the regulator to operate the blow-off valve.
10. A control system for a pump having a discharge conduit with a blow-off valve therein comprising a regulator including balance means, means responsive to the rate of flow thru the pump to urge the balance means in one direction, a diaphragm acting on the balance means to urge it in the opposite direction, a loading line connected to the diaphragm to supply loading pressure thereto, a bleed valve connected to the line including two relatively movable elements to control the loading pressure, an element responsive to the loading pressure connected to one of the valve elements to move it, a pressure responsive member movable in response to the pressure in the discharge conduit, cam means connecting the pressure responsive member to the other valve element, and means controlled by the regulator to operate the blow-off valve.
11. A control system for a pump having a discharge conduit with a blow-off valve therein comprising a regulator including balance means, means responsive to the rate of flow thru the pump to urge the balance means in one direction, a diaphragm acting on the balance means to urge it in the opposite direction, a loading line connected to the diaphragm to supply loading pressure thereto, a bleed valve connected to the line including two relatively movable elements to control the loading pressure, an element responsive to the loading pressure connected to one of the valve elements to move it, a pressure responsive member movable in response to the pressure in the discharge conduit, cam means connecting the pressure responsive member to the other valve element, means operated by the regulator to produce a variable loading pressure, means responsive to the last named loading pres-

sure to control the blow-off valve, and means responsive to the speed of the pump to vary the last named loading pressure.

12. A control system for a pump having a discharge conduit with a blow-off valve therein comprising means to produce a regulated loading pressure, a regulator including balance means, means responsive to the loading pressure to urge the balance means in one direction, means responsive to the flow thru the pump to urge the balance means in the other direction, and means controlled by the balance means to operate the blow-off valve.

13. A control system for a pump having a discharge conduit with a blow-off valve therein comprising means to produce a regulated loading pressure, a regulator including balance means, means responsive to the loading pressure to urge the balance means in one direction, means responsive to the flow thru the pump to urge the balance means in the other direction, and means controlled by the balance means to operate the blow-off valve, a second regulator controlled by the balance between the loading pressure and the pressure in the discharge conduit, and means controlled by the second regulator to control the speed of the pump.

14. A control system for a pump having a discharge conduit with a blow-off valve therein com-

prising means to produce a regulated loading pressure, a regulator including balance means, means responsive to the loading pressure to urge the balance means in one direction, means responsive to the flow thru the pump to urge the balance means in the other direction, means controlled by the balance means to operate the blow-off valve, a second regulator controlled by the balance between the loading pressure and the pressure in the discharge conduit, means controlled by the second regulator to produce a second loading pressure, and means responsive to the second loading pressure to control the speed of the pump.
